UNITED STATES PATENT OFFICE.

DANIEL N. HUMPHREY, OF TORRINGTON, CONNECTICUT.

ADJUSTABLE WINDOW-SCREEN.

1,260,385.

Specification of Letters Patent. Patented Mar. 26, 1918.

Application filed May 31, 1917. Serial No. 171,988.

To all whom it may concern:

Be it known that I, DANIEL N. HUMPHREY, a citizen of the United States, residing at Torrington, in the county of Litchfield and 5 State of Connecticut, have invented certain new and useful Improvements in Adjustable Window-Screens; and I do hereby declare the following to be a full, clear, and exact description of the invention, such as 10 will enable others skilled in the art to which it appertains to make and use the same.

This invention relates to improvements in adjustable window screens.

The object of this invention is to provide 15 a screen equipped with novel means whereby it may be adjusted to fit various size window frames and at the same time exclude and obviate all openings and exits, which will permit flies to enter from the exterior 20 to the interior.

A further novelty of this invention is to provide an adjustable window screen, which comprises a pair of upper sections and a pair of lower sections, each pair being 25 adjustably connected together and the upper and lower sections being adjustably connected together, thus the screen sections may be adjusted for heights and widths to compensate for window frames of various 30 sizes and the sections provided with means whereby they may be held in adjusted position.

A still further object of this invention is to provide an adjustable window screen of 35 this character, which will be simple, durable and efficient, and which may be manufactured and sold at a comparatively low cost.

With these and other objects in view, the 40 invention consists in the novel combination and arrangement of parts hereinafter more fully described and set forth in the claims hereto appended.

In the drawings:

45 Figure 1 is a front elevation illustrating the manner in which the invention is assembled and applied in use,

Fig. 2 is a transverse sectional view taken on the line 2—2 of Fig. 1,

50 Fig. 3 is a vertical sectional view taken on the line 3—3 of Fig. 1,

Fig. 4 is a perspective view of one section of one pair,

55 Fig. 5 is a fragmentary perspective view of the other section of the pair,

Fig. 6 is an enlarged detail sectional view illustrating the manner in which the pairs of sections are adjustably held together.

Like numerals of reference designate corresponding parts in all the figures of the 60 drawings.

Referring to the drawings, the numeral 1 designates the screen in its entirety, and it comprises an upper screen member 2 and a lower screen member 3. The upper screen 65 member comprises a pair of sections 4 and 5 respectively, while the lower screen member 3 comprises the sections 6 and 7 respectively. The lower screen member 3 is slidably and adjustably mounted in the upper screen member 2 for compensating for window frames of various heights. The sections of the upper and lower screen members are adjustably connected together with one another, compensating for windows of various widths.

The sections 4 and 5 of the upper screen member, each comprise a rectangular frame having the inner side rails 8, top rails 9 and bottom rails 10 and enlarged outer side rails 70 11 to which is secured a suitable screen material 12. The side rails 11 of each of the sections 4 and 5 are enlarged and project laterally beyond the plane of the top and bottom rails 9 and 10 on one side face thereof as shown, and the purpose of which will be hereinafter more fully described. The outer side rails 11 of the sections 4 and 5 of the upper member 2 project laterally as described in opposite directions, thus they 80 85 constitute stops limiting the inward movement of the sections 4 and 5, relatively to one another when slidably and adjustably connected together as will be hereinafter more fully described.

The outer side rails 11 of each of the sections 4 and 5 are provided on one face with the vertically extending dove-tail grooves 13, which are adapted to receive dove-tail ribs 14 arranged on the outer enlarged side rails 100 11 of the bottom section of the lower member 3. It is to be understood that the construction of the lower member 3 is identical with the construction of the top member 2. Thus when the dove-tail ribs on the enlarged outer rails 11 of the outer member are slidably fitted in the dove-tail grooves 13, in the enlarged outer rails 11 of the top members, they may be adjusted to fit window frames of various heights.

95

105

110

The dove-tail ribs in the outer enlarged rails 11 of the lower member 3 are provided with a plurality of relatively spaced recesses 15, in which is adapted to be removably fitted, the reduced end 16 of the locking member 17. The locking member 17 is arranged to extend through the outer face of the enlarged side rails 11 of the upper member 2 as shown in Fig. 6.

10 The enlarged side rails 11 of the upper member 2 are provided adjacent their lower ends with transversely arranged recesses 18, which open out into the dove-tail grooves 13 of each of the sections 4 and 5. The inner 15 end of the locking member 17 is provided with a circular enlargement 19, which has arranged on one face or formed integrally therewith, the member 16 and the enlargement 19 is adapted to be movable in the recess 18. A coiled spring 20 surrounds the shank 17 and has one end bearing against the inner wall of the recess 18, while its opposite end engages the enlargement 19, thus normally urging the member 16 into engagement with any of the recesses 15 in the vertical ribs 14 on the enlarged side rails 20 of the sections 6 and 7 of the lower member 3.

The outer end of the locking member 17 30 is provided with an enlargement 21, which constitutes a handle, which facilitates the withdrawing of the member 16 from the recesses to permit the upper sections 4 and 5 respectively to be slidably adjusted on the lower sections 6 and 7 respectively of the lower member 3, thus it can be understood that the sections of each of the members 2 and 3 may be adjusted to compensate for window frames of various heights.

40 The top and bottom rails of the sections 6 and 7 of the lower member 3 respectively are provided with transversely extending dove-tail ribs 22, which are adapted to be slidably arranged in dove-tail grooves 23 formed 45 in the top and bottom rails of the sections 4 and 5 of the top member 2, and the inner side rails 8 of the sections 4 and 5 are adapted to abut the inner side faces of the enlarged side rails 11 when fitted together to 50 limit the inward adjustment of the same, thus it can be seen that the sections 4 and 5 of each of the members 2 and 3 respectively may be adjusted laterally to compensate for window frames of various widths and the 55 locking member 17 will hold the frames in

their adjusted positions and against shifting movement when assembled.

It is to be understood that by the connections as described, all openings are eliminated so that flies or other insects on the exterior of the building cannot crawl into the interior thereof when the screen has been applied to a window frame.

It is also to be understood that the lower member 3 comprises the sections 6 and 7, 60 which are identical in construction with the sections 4 and 5 of the top member 2 respectively.

In assembling the device:

The sections 4 and 5 and 6 and 7 of the 70 members 2 and 3 respectively are adjustably connected together by the ribs 22 slidably fitted in the grooves 23 of their respective section; the lower member 3 is then slidably and adjustably mounted in the grooves 13 75 of the upper member 2; thus the lower member 3 is adjustably connected to the top member 2 compensating for windows of various heights; the pins are then drawn outwardly against the tension of the spring 80 20 and when released will seek a recess 15, thus holding the sections in their adjusted positions.

What is claimed is:

An adjustable window screen comprising 85 upper and lower members, each member comprising a pair of sections, each section of the upper and lower members comprising rectangular frames having inner side rails, top and bottom rails and outer enlarged side rails, the outer enlarged side rails of the upper member provided with vertical dove-tail grooves, the outer enlarged side rails of the lower member provided with dove-tail ribs slidably fitted in 95 the grooves of the top member, means carried by the top member and engaging the ribs of the lower member for adjustably holding the members together, the top and bottom rails of the sections of each of the 100 members provided with dove-tail ribs and grooves to adjustably connect the sections of each of the members together, as and for the purpose specified.

In testimony whereof I affix my signature 105 in presence of two witnesses.

DANIEL N. HUMPHREY.
